Application April 4, 1945, Serial No. 586,482

5 Claims. (Cl. 112—95)

1

This invention concerns embroidery machines and refers more particularly to the platen rods which engage the shuttle guides of the so called Swiss embroidering machine.

In these machines, as is well known in the art, the driver bar actuates the shuttle guides by means of the platen rods, and the rods are held on the bar by means of a screw and interposed leaf spring, it being necessary that the connection between the two should be resilient. Various constructions have been resorted to in attempts to produce a resilient connection between the driver bar and platen rod which would fix the rod firmly against movement longitudinal to itself, without substantial increase in the size or weight of either member.

In solving the above problem it was found desirable to provide a platen rod with two small recesses on its upper surface and located inwardly of the curve connecting the body of the rod to a substantially vertical upward extending end portion. The leaf spring is then provided with fingers which extend down into these recesses, preventing outward longitudinal movement of the platen rod. A further feature of this rod is that, if the recesses are formed by stamping, a slight bulge extends laterally from the rod, effectively preventing inward longitudinal movement thereof by reason of contact with the sides of the slot in which the bar rests. This eliminates the present expedient of forming a slight but sharp downward angular extension of the body of the bar adapted to engage the bottom surface of the slot in which the bar rests in order to fix it against inward longitudinal movement.

In operation, the platen rod extends inwardly from the driver bar to the shuttle guides, actuating the latter, in manner well known in the art. The fingers and recesses of the present invention prevent outward longitudinal movement of the platen rods, which is undesirable and results in a lapping of the coacting surfaces of rod and bar which promotes sliding instead of the desired frictional engagement.

The invention will appear more clearly from the following detailed description when taken in connection with the accompanying drawings showing, by way of example, preferred embodiments of the inventive idea.

In the drawings

Figure 1 is a top elevation of the driver bar, platen rod and leaf spring clamp.

Figure 2 is a longitudinal vertical section of the same along the line 2—2 of Figure 1.

2

Figure 3 is a transverse vertical section of the same along the line 3—3 of Figure 1.

Figure 4 is a perspective view of the improved platen rod.

Figure 5 is a side elevation, partly in section, of the invention in operative position on an embroidery machine.

Figure 6 is a perspective view of the improved leaf spring clamp.

Figure 7 is a perspective view of the conventional driver bar in combination with which the invention is adapted to operate.

Referring to Figure 5, the conventional Swiss embroidery machine 10 is revealed as comprising a fabric frame 11 slidably mounted between guides 12, 13. Needles 14 and punches 15 are detachably mounted on their respective holders 16, 17, the two latter being separately actuatable axially of the needles and punches for the purpose of punching and embroidering the work which is held in the frame 11 by the gripping bars 18. The presser fingers 19 are mounted on a finger bar 20 which is in turn mounted on the rocker bar 21. The shuttle bar 22 carries a multiplicity of shuttle guides 23 containing the shuttles, not shown. The driver bar 24 is formed with slots 25, 25A in which the upper and lower platen rods 26, 27 fit. The lower platen rods 27 are detachably and firmly held in slots 25A, as by a plate 28 and screw 29. The upper platen rods 26 are resiliently connected to driver bar 24 in slots 25 by leaf spring clamp 30 and screw 31 engaging the threaded hole 31A. The platen rods 26, 27 engage the shuttle guides 23 to actuate the same.

The platen rod 26 comprises an elongated body portion 32 of substantially rectangular cross section adapted to fit in the slots 25 of driver bar 24. The tip 33 of rod 26 is parallel to body portion 32 and is connected thereto by a sharp downwardly and outwardly curved portion 34 whereby the rod 26 is locked against outward movement relative to driver bar 24. The opposite end 35 of platen rod 26 extends substantially vertically upward. So much of platen rod 26 is conventional.

The invention consists in forming the body 32 thereof with two recesses 36 formed in the top surface thereof adjacent the upturned end portion 35, said recesses 36 preferably being formed by stamping so as simultaneously to

form laterally extending bulges 37 on body 32 below recesses 36, the invention also including fingers 38 formed on spring clamp 30 and adapted to engage the recesses 36.

Spring clamp 30 is a substantially arcuate leaf spring comprising two substantially chordal

under surfaces 39 adapted to bear upon driver bar 24 and platen rods 26, and further comprising holes 40 spaced at intervals to permit the passage of screws 31 to the tapped holes 31A of the driver bar 24. An apron 41 extends downwardly from the body 30, having recesses 42 for the platen rods 26, the sides of the recesses 42 corresponding to the body 32 of rods 26 with recesses 36, and thus including the fingers 38 adapted to engage recesses 36.

The operation of the embroidery machine 10 is more positive due to the presence of the modifications constituting the invention. In particular, the tips 33 of platen rods 26 engage the shuttle guides 23 and are not deflected outwardly by the engagement, since the fingers 38 engaging recesses 36 positively position the rods 26 axially. The bulges 31 engage the sides of slots 25 to prevent inward axial movement of rods 26. The requirement is thus met of a positive connection between platen rods 26 and driver bar 24, the connection still being resilient due to spring clamp 30, the requirement of resiliency being well understood in the art.

It is apparent that the specific illustrations shown above have been given by way of illustration only and not by way of limitation, and that the structures above described are subject to wide variation and modification without departing from the scope of intent of the invention, all of which variations and modifications are to be included within the scope of the present invention.

What is claimed is:

1. In an embroidering machine comprising a driver bar having slots formed therein, said machine further comprising a platen rod adapted to fit in said slots and a substantially arcuate spring clamp adapted to bear on said driver bar and platen rod to resiliently position said rod in said slots, said platen rod comprising an elongated body portion of substantially rectangular cross section and a sharply downwardly and outwardly curved tip portion extending parallel to said body portion and adapted to engage a shuttle guide of said machine, said platen rod further comprising at its opposite end a substantially vertically upward extending portion, said spring clamp further comprising an apron portion extending downwardly therefrom, the combination of recesses formed in the upper surface of said body portion adjacent said upward extending portion and finger portions formed on said apron portion and adapted to engage said recesses.

2. In an embroidering machine, in combination with a driver bar having slots formed therein, a platen rod adapted to fit in said slots and engage at one end thereof a shuttle guide of said machine, an upstanding portion on said rod at

the end opposite the shuttle guide engaging end, the said bar having a pair of marginal pressed recesses at the juncture of the rod and upstanding portion, lateral bulges formed by the material pressed from the recesses for contacting the driver bar to prevent relative forward movement between the said rod and bar, a spring clamp adapted to resiliently bear upon said driver bar and platen rod to resiliently connect the two together and position the said rod in said slots, and finger portions on said spring clamp for engagement with the forward ends of said recesses to prevent relative rearward movement between the bar and rod.

3. A platen rod for an embroidery machine said rod comprising a horizontal portion and a vertical portion bent therefrom, a pair of marginal recesses in the horizontal portion at the juncture thereof with the vertical portion and bulging portions extending laterally from a point below said recesses.

4. In an embroidering machine, in combination with a driver bar having slots formed therein, a platen rod adapted to fit in said slots and engage a shuttle guide of said machine, said platen rod comprising a horizontal portion, a vertical end portion extending therefrom and being formed with a recess therein at the juncture of the horizontal and vertical portions and a spring clamp adapted to resiliently bear upon said driver bar and platen rod to resiliently connect the two together and position said rod in said slots, said spring clamp comprising a finger portion adapted to engage the forward end of said recess.

5. In an embroidery machine comprising a driver bar having slots formed therein, said machine further comprising a platen rod adapted to fit in said slots and a substantially arcuate spring clamp adapted to bear on said driver bar and platen rod to resiliently position said rod in said slots, the said platen rod having a horizontal portion and an upstanding end extending therefrom, the improvement comprising recesses formed in said platen rod at the juncture of the horizontal portion and upstanding end, and fingers formed by said spring clamp adapted to engage the forward ends of said recesses for the prevention of axial movement of said rod relative to said bar.
